FOOD GRATER

Solomon Silberberg, Bellrose, N. Y.

Application March 1, 1957, Serial No. 45,038

Term of patent 14 years

(Cl. D89—1)

Fig. 1 is a perspective view of a food grater, showing my new design;

I claim:

The ornamental design for a food grater, substantially as shown.
